(57) **CLAIM**

The ornamental design for a switch panel as shown and described.

DESCRIPTION

FIG. 1 is a front, right and top perspective view of a switch panel showing my new design;

FIG. 2 is a rear, left and bottom perspective view thereof;

FIG. 3 is a front elevational view thereof;

FIG. 4 is a rear elevational view thereof;

FIG. 5 is a top view thereof;

FIG. 6 is a bottom view thereof;

FIG. 7 is a left view thereof; and,

FIG. 8 is a right view thereof.

The broken lines illustrate portions of the switch panel that form no part of the claimed design.
